UNITED STATES PATENT OFFICE.

JOEL T. CRISWELL, OF COLLAMER, PENNSYLVANIA.

MITERING-MACHINE.

SPECIFICATION forming part of Letters Patent No. 363,119, dated May 17, 1887.

Application filed February 19, 1887. Serial No. 228,186. (No model.)

To all whom it may concern:

Be it known that I, JOEL T. CRISWELL, a citizen of the United States, residing at Collamer, in the county of Chester and State of Pennsylvania, have invented certain new and useful Improvements in Mitering-Machines; and I do hereby declare the following to be a full, clear, and exact description of the invention, such as will enable others skilled in the art to which it appertains to make and use the same.

This invention relates to improvements in mitering-machines; and it consists in the novel construction and arrangement of parts, as will be hereinafter fully described.

The annexed drawings, to which reference is made, fully illustrate my invention, in which—

Figure 1 represents a perspective view of my device. Fig. 2 is a top view of the same. Fig. 3 is a rear view. Fig. 4 is a side view, and Figs. 5, 6, and 7 are detail views.

Referring by letter to the accompanying drawings, A designates the base or platform of the machine, which is hinged at a to a cross-strip, b, to the upper surface of which is hinged two standards, c c', that are connected at their upper ends by a lever, d, which is pivoted to the standard c, and the opposite end has a hook, e, which engages a bolt, f, in the standard c', whereby the two standards are coupled to one another and are held parallel vertically. These standards are provided with vertical kerfs g, which are designed to receive the saw, and each has adjustable guide-strips h, having horizontal slots i for set-screws j, whereby the kerf in each standard can be widened or made narrow for different saws, and can be removed for trimming or smoothing their edges. The platform aforesaid is provided with a curved slot, k, the arc being struck from the point or pivot l, which connects an adjustable plate, m, thereto, which is provided with a pointer, n, and a bolt, o, which passes through the curved slot, and is provided with a thumb-nut, p, on the under side of the platform, and the portion A is provided with legs q, on which the machine rests. Upper wings, r, are hinged at s to the top of the movable plate, and the same have curved arms t secured to it, which pass through loops u on the upper end of a fixed arm, v, secured to the upper face of the mova-

ble plate, and is provided with a thumb-screw, w, which is designed to hold the movable wing r in a fixed position when set for mitering. These wings are each provided with projecting arms x, which are provided with kerfs y at their upper ends, designed to receive a bar, z, of a clamp, a', which consists of two arms, b', at the lower end of one of which is a screw, d', that serves to tighten the board or material to the wing and hold it fast while sawing a miter.

To the under side of the hinged platforms are secured curved arms e' e', which pass through loop on the end of the curved arms f' f', secured to the cross-piece of the frame. A thumb-screw, a'', serves to bind the two curved arms to one another when said platform is set at an angle to the cross-bar or when the same is in a horizontal position.

These arms are held in any fixed position by the thumb-screw, which passes through the loop, and the point thereof pressing against the arms fixed to the cross-piece. This arrangement allows the hinged platform to be adjusted to different positions in cutting miters, and can be held firmly by the set-screw, and the various parts are so arranged to allow adjustments to any desired angle, and are also provided with gage-marks, whereby the parts can be set and at the same time held in the proper relation to one another.

It will be seen that the machine herein described is capable of being adjusted to almost any angle, and the different gages will allow the different adjustable portions to be set for cutting miters for wagon-seats, window-frames, and also for cutting straight edges, and will hold material in position while the different sawed portions are being nailed, screwed, or glued together, and the standard c' can be readily thrown back in order to allow the operator to have access to the material while securing the parts together; and it will be further seen that but one operator is required to operate the machine, as the clamping-irons hold the material firmly while being secured, and any desired angles can be cut for various purposes, and at the same time it is simple in construction, not liable to get out of order, and cheap to manufacture.

Having described my device, what I claim, and desire to secure by Letters Patent, is—

1. In a mitering-machine, the standards

hinged to the intermediate portion, *b*, of the table, and provided with the adjustable guide-strips *h h* and pivoted hook *d*, in combination with the hinged platform *A*, plate *m*, pivoted 5 to said platform, wings *r*, hinged to said plate, and arms *v t*, secured, respectively, to the wings and plate by the thumb-screw engaging said arms, as shown, the whole as and for the purpose set forth.

10 2. In a mitering-machine, the combination of the main body portion, the swinging or pivoted plate and hinged wing *r*, and curved arm *t* and arm *v*, provided with the screw *w*, as and for the purpose set forth.

15 3. In a mitering-machine, the combination, with the hinged platform provided with the slot *k*, the plate *m*, pivoted thereto, having the bolt to engage said slot, wings *r*, hinged to said plate, and having the arm provided with 20 the kerf, of the clamp *a'*, consisting of the arms *b' b'*, cross-piece *z*, and screw *d'*, said piece adapted to engage the kerf *y* in the arm *x*, the hinged standards *e e'*, having the guide-strips *h h*, kerf *g*, and pivoted hook *d*, as and for the 25 purpose set forth.

4. In a mitering machine, the platform provided with legs and composed of two hinged

sections and an intermediate section, *b*, secured and held in different positions by means of the curved arms *e' f'*, engaging one another 30 and secured in position by the set-screw *a'*, in combination with the standards *e e'*, plates *m*, and wings *r r*, constructed substantially as described.

5. The mitering-machine herein described, 35 consisting of the platform composed of hinged sections, the plates constructed as shown and pivoted to the upper surface thereof, and provided with the curved arms *v*, having loops *u* and screw *w*, the hinged wings connected to 40 said plates and provided with the curved arms *t*, extension *x*, having the kerf *y*, the hinged standards having the adjustable guide-strips and the connecting-hook, and the parts of the clamp *a'*, whereby the material is held in place 45 while the said parts are being connected, as and for the purpose set forth.

In testimony whereof I affix my signature in presence of two witnesses.

JOEL T. CRISWELL.
